(57) **CLAIM**

The ornamental design for a bedstead, as shown and described.

DESCRIPTION

FIG. 1 is a left front perspective view of a bedstead showing my new design;

FIG. 2 is a side view, the opposite side being a mirror image thereof;

FIG. 3 is a front elevational view thereof; and,

FIG. 4 is a rear perspective view of the footboard section thereof.

The views of the bedstead not shown form no part of the claimed design. The broken lines depicting bed rails and feet represent environmental elements only and form no part of the claimed design.

1 Claim, 3 Drawing Sheets

FIG. 3

FIG. 2
